(**) Term: **14 Years**

(57) **CLAIM**

(21) Appl. No.: **29/233,499**

The ornamental design for a pressure gage with axial connector, as show.

(22) Filed: **Jul. 1, 2005**

DESCRIPTION

(51) **LOC (8) Cl.** 10-04

FIG. 1 is a perspective view showing the front of our new design;

(52) **U.S. Cl.** **D10/85**

FIG. 2 is a perspective view showing the rear of our new design;

(58) **Field of Classification Search** D10/85;

FIG. 3 is a right side elevation view of our new design, the left side being a mirror image thereof; and,

73/715-722, 431, 732-733; 200/83, 83 B,

FIG. 4 is a top plan view of our new design, the bottom plan being a mirror image thereof.

200/83 C, 83 L; 324/110-116, 119

See application file for complete search history.
